ADJUSTABLE LEG REST

Henry J. Sokolowski, Pierson, Iowa 51048

Filed Mar. 10, 1971, Ser. No. 123,130

Term of patent 7 years

Int. Cl. D6—02

U.S. Cl. D6—32

FIG. 1

FIG. 2

FIG. 3

FIG. 4

FIG. 1 is a top perspective view of an adjustable leg rest showing my new design;

FIG. 2 is a side elevational view;

FIG. 3 is an end elevational view; and

FIG. 4 is a bottom plan view.

I claim:

The ornamental design for an adjustable leg rest, substantially as shown.
